Specification of Letters Patent. Patented Aug. 15, 1916.

Application filed April 19, 1909, Serial No. 490,820. Renewed June 3, 1916. Serial No. 101,642.

To all whom it may concern:

Be it known that I, NEWTON W. THOMAS, a citizen of the United States, residing at Cleveland, in the county of Cuyahoga and 5 State of Ohio, have invented certain new and useful Improvements in Presses, of which the following is a specification.

In laundrying cuffs or wrist bands attached to shirts or shirtwaists or other garments, other than by hand, it has been customary up to the present time to iron them flat or partly bend them in a press of suitable size to receive the cuff, or to pass them underneath a heated roller which operates in conjunction with a suitable table or bed, and if it should be desired to have the cuff turned for receiving link cuff buttons, then the cuff must be curved at its center either by some additional means or else the 10 wearer must bend the cuff around into shape usually with the result that the outer covering becomes cracked where the bend occurs. In fact if the cuffs are ironed flat and are then bent abruptly, the outer covering is 15 broken in a very short period of time due to the undue strain on the fabric.

The object of the present invention, therefore, is to provide a cuff press for forming and ironing cuffs of the link or U-shaped 20 type and the machine is of a construction such that the moistened cuff may be placed around a suitable former which is of the proper shape such that the edge of the cuff adjacent to the sleeve is formed in U-shape 25 with the sides thereof substantially parallel while the outside edge of the cuff, adjacent to the hand, diverges from the bend or center outward toward the corners thus causing the side edges to diverge outward from the 30 wrist to the corners also. After the cuff has been placed upon this member it is then moved into contact with suitable ironing dies, which have ironing faces conforming to the configuration of the outside of the 35 former and adapted to dry the cuff and put a finish on the outside face thereof and set it in the link shape ready to wear without further forming or shaping previous to applying the cuff buttons.

40 The invention more specifically relates to a suitable former adapted to be moved up and down by suitable foot operated mechanism and to have the cuff bent over

the same and to be moved up into contact with a pair of swiveled dies which are normally swung open, but which are arranged to move in against the former in a manner such that their finished faces conform to the configuration of the former.

45 Invention also resides in a flexible metal plate operating in conjunction with the dies as they close about the former, the object of this plate being to form a continuous curved ironing surface bridging the gap between the upper inner edges of the dies and preventing any impression of the edges of the dies being left on the cuff about the curved portion thereof.

55 Invention also resides in the arrangement of suitable mechanism for quickly moving the former into engagement with the dies and creating an additional pressure at the end of such movement and finally causing a positive quick return of the parts to normal position.

60 The invention still further relates to certain details of construction employed in conjunction with several parts of this machine and clearly set forth in the accompanying drawings, specification and claims.

65 Referring to the drawings Figure 1 is a front elevation of my device; Fig. 2 is a vertical section through the center of the machine; Fig. 3 is an enlarged view in side elevation of the treadle mechanism when in one position; Fig. 4 is a similar view with the treadle mechanism in another position; Fig. 5 is an enlarged view of the former and dies in open position; Fig. 6 is an enlarged view of the former and dies in closed 70 or ironing position; Fig. 7 is a sectional view of a yielding coupling between the treadle mechanism and the former operating shaft being a modification of the construction shown in Fig. 2; and Fig. 8 is a top 75 plan view of the former.

80 Any preferred form and construction of parts may be employed in carrying out my invention, but I have shown one form in the drawings which meets the requirements with great efficiency, and in such embodiment 1 represents a suitable upright or column provided with a base 2 and an upper extension or arm 3 together with a suitable faced portion 4 and a suitable guiding bracket 5. The 85 arm 3 carries a pair of yoke-shaped mem-

bers 3' one in the front and one in the rear, and these members are provided with suitable bearings 6, the two on the left, as shown in Figs. 1 and 5, supporting one die member 7, and the two on the right supporting a die 8. Each of these dies is provided with a chamber 9 upon the inside and with hollow trunnions 10 passing out through the bearings 6 in the yokes. Communicating with the opening of one of the trunnions of each die member and integral therewith and upon the inside is a downwardly extending pipe 11 for a purpose to be described. Each die member is still further provided with an ironing face 12 both of which are curved at their upper edges and diverge from top to bottom and from the front outward toward the rear in a lateral direction so that when they are swung inward toward the center their front edges are substantially parallel and near together while the back and bottom edges diverge outward toward the lower back corners, the back edges being farther apart throughout than the front edges, as shown. The substantially parallel front edges are shown in Fig. 1 and the diverging and much more widely separated back edges are shown in Fig. 6. The forward end of each journal of the two ironing dies is provided with a steam supply pipe 13 which passes through a suitable stuffing box 14 in the trunnion. These pipes discharge into the die member and water and exhaust steam passes out through the pipe 11 and through a discharge pipe 15 mounted in the rear journal of each of the die members. Stuffing boxes 16 are arranged at these points to prevent leakage. The normal tendency of these dies is to occupy the position shown in Fig. 5 so that their inner ironing faces are substantially at an obtuse angle to each other. Secured to these dies is an ironing plate 17 which is of thin metal and is adapted to conform readily to the configuration of the inner ironing faces of the dies and it is normally held in position relative thereto by means of lips 18 extending up upon the front faces of the die members and provided with slots 19 for receiving screws 20 secured in the dies. The operation of this plate and its object will be given later.

Mounted upon the finished face portion 4 is a guiding member 21 which is provided with a vertical opening 22, shown in dotted lines in Fig. 1 and having at the top and bottom thereof stuffing boxes 23 and 24. These stuffing boxes receive a vertical shaft 25 which, as shown in Fig. 2, is provided with a vertically disposed opening 26 connected by a port 27 with a longitudinal groove 28 in the inner wall of the guiding member. This groove 28 communicates with an opening 29 to which a suitable steam supply pipe may be connected. The shaft 25 is further provided with a vertically disposed

opening 30 connected by a port 31 with a vertical groove 32 which, in turn, is in communication with an opening 33 in which an exhaust pipe may be inserted. The upper end of this shaft has mounted upon it a platform 34 which is provided with a pair of bearings 35 and a pair of bearings 36 and the axes of these two pairs of bearings are at an angle to each other as shown. Mounted upon a shaft 38 in each pair of bearings 35 and 36 is a roller 37 provided with hooks 39 for a purpose to be described. Upon the projected end of each of these shafts 38 is a ratchet wheel 40 adapted to be engaged by a suitable pawl 41. The object of these rollers and their pawls, ratchet wheels and hooks will be later fully set forth.

Mounted within the pairs of bearings 35 and 36 and upon the platform 34 is a block 42 having an opening 43 therein, shown in dotted lines in Fig. 8, into which the shaft 25 having the openings 26 and 30 extends. This block is provided with a vertically disposed hollow former 44 which is best shown in Fig. 5 and in plan in Fig. 8. This former is narrow at its front and the side edges at this point are nearly parallel while the side faces diverge from these front edges backward to edges which are a greater distance apart and diverge outward slightly from top to bottom. The upper portion of this former is curved as shown. Suitable ears 45 are provided at the base and on each side of the former and they are adapted to receive rods 46. Upon this former is a suitable padding of felt 47 and an outer facing 48 of canvas or other similar material which is drawn down under the rods 46 with the ends passing over the corresponding rollers or drums 37 and secured upon the hooks of these drums. This facing or outer covering may be tightened by rotating the rollers and holding them in such position by the use of the ratchet and pawl construction already described.

It will be seen from the foregoing construction that as the dies 7 and 8 hang in their open position, as shown in Fig. 5, with the ironing plate bent slightly therefrom and the cuff is placed over the former and held tightly down upon the same and the former is moved up, that it will cause the cuff to engage the ironing plate and finally draw the dies in close against the cuff and force it upon the former and since the former may be heated by means of the connections and openings in the shaft and since the dies are heated, then the cuff will be ironed in proper form. The cuff formed by this machine, is, of course, the flat form of cuff usually worn at the present time attached to shirts.

In order to impart an up and down movement to the former, suitable treadle and operating mechanism is provided and it may

be applied directly to the lower end of the shaft 25 by telescoping a reduced portion 25' thereof into a part of the treadle operating mechanism to be described or it may be 5 applied by means of a yielding connection.

In employing the latter construction the shaft 25 is provided with an opening 49 extending well up into the shaft, but not to the point where the ports 27 and 31 enter, 10 and the lower end of the shaft is provided with a ring 50 threaded onto the end of the shaft and provided with an inwardly projecting flange 51 for a purpose to be described. Passing through the opening with 15 in the flange 51 is a rod 52 having a head 53 on the upper end thereof and fitting the inner bore of the opening 49 and adapted for engagement with the flange 51 in its downward movement. This rod is provided with 20 a collar 54 held in place by a suitable set screw 55 and arranged to have mounted between it and the ring 50 a coil spring 56 which normally tends to hold the head 53 upon the flange 51. The lower end of this 25 rod is threaded at 57 and receives a check nut 58 and a hand wheel 59 both of which are threaded on this portion of the rod. The rod 52 is still further provided with a longitudinal key way 60 for a purpose to be described. The hub of the hand wheel is adapted to bear upon the upper edge of a shank 61 provided with an opening 62 to receive loosely the end of the rod 52 which may slide freely therein but is held against 30 rotary movement relative thereto by the reduced end 63 of a screw 64 passing through a boss 65 forming a part of the shank and into the key way 60, and is held against longitudinal movement, after adjustment, by 35 the same screw 64 when it is screwed up. A set screw 26^a may be used in the other construction for engagement with the reduced end portion 25'.

The shank 61 is provided with laterally 40 projecting bosses 66 to which are pivoted suitable links 67 which normally hang down at a slight angle to the vertical as will be hereinafter set forth and have inwardly projecting pins 68 engaging side faces of 45 guiding flanges 69 forming a part of a treadle member 70 pivoted upon a suitable shaft 71 in the base. The links are further provided at their lower ends with shoulders 67' for a purpose to be described. This 50 treadle member 70 has a foot arm 72 and a segmental arm 73 having gear teeth 74 upon the periphery thereof meshing with gear teeth 75 on a crank arm segment 76 mounted upon a transverse shaft 77 carried by 55 suitable supports 78 secured to the base. This crank arm segment 76 is integral with a crank arm 79 carrying at its end a pin 80 projecting laterally from either side thereof and carrying upon each projecting portion a friction roller 81. Both of these roll-

ers are adapted to engage the face 82 of a cam member 83 secured to the lower end of the shank 61. The face 82 of this cam member is substantially horizontal, except for the curved portion 83', and the normal position of the crank arm 79 is that shown in Fig. 2, so that upon the rotation of the crank arm in a clockwise direction the cam member and its shank will be moved upward until the crank arm is in a vertical position as 70 shown in Fig. 4. When the crank arm 79 and its friction rollers are in the position shown in Fig. 2 or in normal position, however, the friction rollers are between the cam face 82 and inwardly projecting flanges 80 84 carried by side members 85 formed integral with the cam member 83. These flanges extend from the end of the cam member nearly to the vertical center of the shank, so that when the crank arm is moved 85 in a counter clockwise direction from vertical position, it will engage the upper faces of these flanges and pull the cam member and its shank downward if there should be any tendency toward their being held against 90 moving downward. The treadle member 70 is further provided with pins 86, one on each side, adapted to engage at a certain time in the cycle of movement of the device under the shoulder 67' of the links 67 as will later 95 be described. The treadle member is still further provided with an ear 87 provided with a slot 88 adapted to receive a pin 89 carried by a treadle bar 90 having a foot arm 91. The normal position of the foot 100 arm 72 of the treadle member 70, when the crank arm 79 is in normal position, is upward, as shown in Fig. 2, while the normal position of the treadle bar 90 is downward with the ear 87 downward and the pin 89 in 105 the left end of the slot 88. Let us assume, for example, that the former is down and the treadle mechanism is in normal position with the foot arm 72 up and the foot arm 91 down, then after a cuff has been placed over 110 the former the operator in placing his foot upon the treadle arm 72 moves it downward causing the segmental teeth 74 to engage the teeth 75 of the crank arm and rotate it in a clockwise direction, thus causing the friction rollers 81 to engage the face 82 of the cam member and move it upward. While this is taking place, the links 67 are being held at a slight angle to the vertical by reason of the pins 68 moving up the side faces 115 120 of the guiding flanges 69. The upward movement of the cam member, however, moves the shank 61, the rod 52 and through the spring 56, the shaft 25, which carries the platform 34 upon which the former is 125 mounted, until the former moves the dies in toward the sides thereof and against the cuff, in the meantime, however, the links 67 carried by the shank 61 have been moved up also until the edge of the shoulders 67' is 130

slightly above the pins 86 so that a further movement of the treadle member carries the pins under the shoulders 67' and causes the links to be moved into vertical position or 5 into parallel alinement with the axis of the shank and rod thus causing a final increased pressure upon the cuff in the finishing of the ironing operation. It is quite obvious that the treadle member with its pins and the 10 links form a toggle arrangement which in being straightened produces a great pressure upon the cuff and locks the parts in this position. During the downward movement 15 of the treadle arm 72, in the above described operation, the treadle bar 90 has been shifted into its upper position, as shown in dotted lines in the drawings, by reason of the pin 89 being engaged by the walls of the slot 88 in the ear 87 upon the treadle member so 20 that to release the parts, which are locked as stated, the operator places his foot upon the treadle arm 91 and moves it downward causing the pin 89 to engage the walls of the slot 88 in the ear 87 and shift the treadle member 25 to the rear, or in a clockwise direction, thus breaking the toggle and causing the crank arm to be moved in a counter clockwise direction until the rollers carried by this crank arm engage the flanges carried by 30 the cam when the former and the connections between it and the shank will be drawn downward positively into normal position. The machine is then ready for another operation. It is, of course, understood that 35 the steam has previously been applied to the several parts in the manner already indicated, and that the dies and former are sufficiently heated to produce effective ironing.

Having described my invention, I claim:—

40 1. In a cuff and wrist band press, in combination, a former, a pair of dies coöperating with the former and having faces adapted to coöperate with the faces of the former, and an ironing plate interposed between the dies and adapted to form a continuous ironing surface about the surface of the former and bridge the gap between the dies.

45 2. In a cuff and wrist band press, in combination, a former, a pair of dies coöperating therewith and adapted to close tightly against the surface thereof, and an ironing plate secured to the faces of the dies interposed between the dies and the former and adapted to move therewith tightly about the former and to provide a continuous ironing surface, and bridge the gap between the dies.

50 3. In a cuff and wrist band press, in combination, a frame, a former movably mounted in the frame, a pair of dies having ironing faces and mounted in the frame and when the former is out of engagement therewith being adapted to swing by gravity outward away from such former, an ironing plate carried by said dies and adapted to

yield with the same and to conform to the surface of the former, means for shifting the former, and means whereby heat may be applied to the parts.

4. In a cuff and wrist band press, in combination, a frame, suitable ironing dies, a former coöperating therewith and movably mounted, an operating member, means between it and said former for causing the latter to be shifted quickly into engagement 70 with the dies, a link also connected with the former and normally held out of straight line position, a pin carried by the operating member and adapted to engage the link and bring it into straight line position and thereby bring about an increased pressure at the 75 end of the ironing operation.

5. In a cuff and wrist band press, in combination, a frame, suitable ironing dies, a former coöperating therewith and movably mounted, a treadle member mounted in the frame, suitable gearing between said treadle member and said former whereby the latter is moved upward into engagement with the dies when the treadle member is moved, a link connected to the former at one end and normally held out of parallel alinement with the vertical axis of the former, and a pin carried by said treadle member and adapted to engage said link and bring the same into 80 straight line position thereby exerting a final increased pressure between the dies and the former.

6. In a cuff and wrist band press, in combination, a frame, suitable ironing dies, a former coöperating therewith and movably mounted, a suitable treadle member, gearing between said treadle member and said former whereby it may be moved upward into engagement with the dies, a link connected to the former at one end and having a shoulder at its lower end, a guide secured to the treadle member and adapted to hold the lower end of said link out of parallel alinement with the axis of the former, and a projection carried by the treadle member and adapted to engage the shoulder on the end of said link and shift the same into straight line position and thereby create an increased pressure between the former and 90 the dies.

7. In a cuff and wrist band press, in combination, a frame, suitable ironing dies, a former coöperating therewith and movably mounted, a treadle member, a crank arm pivoted to the frame, suitable gearing between said crank arm and said treadle member, a cam coöperating with said crank arm, a rod between the former and said cam whereby upon the movement of the crank 110 arm said former is shifted upward into engagement with the dies, a link secured to the connection between the former and said cam, a guide carried by said treadle member and normally holding said link out of parallel 115 120 125 130

alinement with the axis of the former and its rod, and a pin mounted upon the treadle member and adapted to engage under the end of said link and cause an added increased pressure at the end of the upward movement of the former.

8. In a cuff and wrist band press, in combination, a frame, suitable ironing dies, a shaft mounted in said frame, a former on the end of said shaft and coöperating with the dies, a treadle member mounted in the frame, a crank arm mounted in the frame, a cam secured to said shaft and coöperating with the crank arm whereby upon the movement of the latter the former is shifted into engagement with the ironing dies, suitable gearing between said crank arm and said treadle member, a guide secured to the treadle member, a link secured to said shaft and having at its lower end a portion engaging said guide whereby it is normally held out of parallel alinement with the axis of the shaft, and a pin carried by said treadle member and adapted to engage the end of said link and produce an added pressure between the former and its dies.

9. In a cuff and wrist band press, in combination, a frame, a die carried thereby, a bracket extending from said frame and provided with an opening for a shaft and two opposed elongated grooves in the wall about said opening together with exhaust and supply ports leading to said grooves and passing out through the bracket, a shaft slidably mounted in the opening in said bracket and provided with two longitudinal openings one connected by a port with one of said grooves and the other by a port with the other groove in the bracket, a former mounted upon the upper end of said shaft and having an opening therein communicating with the openings in said shaft, and stuffing boxes secured in said bracket about said shaft.

10. In a cuff and wrist band press, in combination, a die, a former, a pad about said former, a rod on each side and at the base of said former, a roller in parallel alinement with each rod, suitable hooks provided upon said rollers, means for holding them against rotation in one direction, and a covering

for said former secured to the hooks and passing under the rods and over the former.

11. In a press, the combination of co-operating pressing members one of which is movable, a slidable actuating member connected to said movable pressing member, a gear segment operatively connected to said actuating member, and an oscillatory gear segment for actuating said first named gear segment.

12. In a press, the combination of co-operating pressing members one of which is movable, a slidable actuating member connected to said movable pressing member, co-operating intergeared segments, means for operating one thereof, and means operatively connecting the other segment to said actuating member.

13. In a press, the combination of co-operating pressing members one of which is movable, a slidable actuating member connected to said movable pressing member, co-operating intergeared segments, means for operating one thereof, and an arm rigid with the other segment and operatively connected to said actuating member.

14. In a press, the combination of co-operating pressing members one of which is movable, a slidable actuating member connected to said movable pressing member, a pivoted treadle having a gear segment rigid therewith, and a gear segment operated thereby and connected to said actuating member.

15. In a press, the combination of co-operating pressing members one of which is movable, a slidable actuating member connected to said movable pressing member, a pivoted treadle having a gear segment rigid therewith, and a gear segment operated thereby and provided with a rigid arm arranged when actuated to move said actuating member.

In testimony whereof I affix my signature in presence of two witnesses,

NEWTON W. THOMAS.
